UNITED STATES PATENT OFFICE.

EDWARD E. THRESHER, OF AURORA, OHIO.

ARTIFICIAL BIRD-TARGET.

1,075,518.

Specification of Letters Patent. Patented Oct. 14, 1913.

Application filed January 11, 1909. Serial No. 471,600.

To all whom it may concern:

Be it known that I, EDWARD E. THRESHER, a citizen of the United States, residing at Aurora, in the county of Portage and State 5 of Ohio, have invented certain new and useful Improvements in Artificial Bird-Targets, of which the following is a specification.

My invention relates to artificial bird-targets, the primary object of the invention being to provide an indestructible artificial target for use in what is known as "trap-shooting," and target being adapted to be suspended and carried through the air in 10 perfect imitation or similitude of a live-bird. These indestructible bird-targets are designed to take the place of live-birds in trap-shooting tournaments, thereby doing away with the cruelty exhibited by sportsmen in live-bird shooting. These bird targets are also designed as an improvement on and a substitute for the so-called "pigeons" or "targets" made of clay now in common 15 use by gun-clubs.

In carrying out the invention, the bird-target is made up of carbonized steel (or 20 other hardened steel calculated to withstand, without material injury or deformity, the shock incident to the impact of the missile shot) plate in the form representative of a flying pigeon or other bird, and so arranged and carried by a carrier-wire or cable that when struck by a missile shot it will automatically change from its substantially horizontal or "flying position" to a 25 substantially vertical or "dead position," the target being carried and suspended in said last mentioned position by said carrier-wire to the carrier-wire actuating-wheel or "trap" where it may be again attached in its "flying position" and reversed and despatched in another direction.

With the above mentioned ends in view, the invention consists in the novel construction, arrangement, and combination of parts, hereinafter described, illustrated in the accompanying drawings showing one of the embodiments of the invention, and particularly pointed out in the appended claims.

Referring to the drawings, forming a part of this specification, Figure 1, is a side elevation of an artificial bird-target in its normal or flying position. Fig. 2, a top 50 plan view of the same, a portion of the trolley-wheel housing of the traveling carrier being broken away for the purpose of

clearer illustration of the parts. Fig. 3, a side elevation of a portion of the improved carrier-wire or cable, and one of the actuating-wheels or "traps," the bird-target 60 being shown carried in its substantially vertical or "dead position." Fig. 4, an end view of the improved traveling-carrier, the bird-target, proper, being detached. Fig. 5, a plan view of the underside of same with 65 depending swivel-carrying casing or housing removed, the oppositely-disposed latching-bolts or plates and eccentrically-mounted spring-resisted laterally-extensible actuating bolts being in their contracted or retracted position. Fig. 6, a similar view of 70 same in their expanded or projected position as they appear when the traveling-carrier is carrying the bird-target in its normal or flying position as indicated in Figs. 75 1, and 2.

The artificial bird-target proper, comprises two parts of sheet metal 1, conforming in their outline and contour to the outline and contour of the body neck and head 80 portions of the bird represented. The parts 1, are pivotally connected along their lower edges, in the present instance, by means of a hinge 2, secured within the lower marginal edges of the parts 1, by means of rivets 85 3. The upper marginal or free edges of the parts 1, are bent inwardly to provide front and rear shoulder portions 4 and 5, respectively, and provide an intermediate 90 rectangular shaped carrier receiving opening 6, adapted to receive and contain the traveling carrier hereinafter described, when the bird target is in its horizontal or flying position as shown in Figs. 1 and 2, 95 of the drawings.

The upper marginal or free edges of the parts 1, forming the body of the bird-target, are provided with wings 7, of sheet metal conforming in their outline and contour to that of the wings of a flying bird, 100 said wings, in the present instance, being secured to the upper free edges of the parts 1, forming the bird body by means of rivets 8. The front shoulder portions 4, are provided, in the present instance, with reinforcing strips 9, provided with stems 9^a, secured by means of rivets 10. The rear shoulder portions 5, in the present instance, are provided with tail stems 11, extending 105 upwardly and rearwardly therefrom, and secured, in the present instance, to the rear oval shaped portions 1^a, of the bird-body 110

by means of attaching stems 12, and rivets 13. It is obvious, however, that the tail stems may be formed integral with the bird body portions 1^a, if desired. The front or head portions of the parts 1, are connected by a cross pin the head 14, (see Fig. 2) of which forms a stop to limit the outward movements of the upper or free sides of the parts 1, said cross pin being screw threaded at its opposite end 14^a, and threaded into the opposite head portion of the opposite part. It will be observed that the cross pin forms the eye of the bird-target and the shank of the cross pin near the head 14, is adapted to loosely play in the opening therefor.

The tail 15, of the bird-target comprises a plate of sheet metal secured beneath the tail stems 11, by means of guide pins 16, extending through rearwardly converging guide slots 17, of the tail stems. The tail 15, is provided with a depending portion 15^a, carrying a contact-strip 18, of substantial U-shape in outline the front marginal edges 18^a, of said contact-strip being adapted to abut against the oval shaped rear portions 1^a, of the bird-target body.

By reason of the construction described it will be observed that the upper free edges of the parts 1, forming the body neck and head portions of the bird-target are adapted to have a limited movement to and from each other for coöperating with the latching and carrying mechanism of the traveling carrier to be now described. The traveling carrier comprises a carrier-plate 19, provided on its under sides with guide flanges 20. As a means for suspending and carrying the bird-target through the air the carrier plate is, preferably, provided with a trolley-wheel 21, mounted in a housing 22. A carrier-wire or cable is adapted to be suitably suspended between two carrier-wheels or "traps" 23, one of which is shown in Fig. 3, of the drawings, and the upper member 24, of the carrier-wire is adapted to pass through suitable openings 25, of the housing 22, and under the trolley-wheel 21, while the lower ends or members 26, of the carrier-wire or cable are secured at their ends to attaching bolts 27, of brackets 28, secured to the upturned ends 19^a, of the carrier-plate.

The traveling carrier latch engaging and actuating mechanisms are mounted on the under side of the carrier-plate 19, and inclosed within a depending housing 29, secured to the sides of the guide flanges 20, by means of screws 30. The housing 29, is provided at its opposite sides with slots 31, through which the laterally extensible actuating bolts, hereinafter described, are adapted to extend or project while in their expanded or projected position.

When the bird-target is released from its horizontal or flying position, it is caused to

assume and is suspended in its substantially vertical or "dead position" by means of a connecting bar or link 32, having one end secured to the cross pin intermediate the sides of the head of the bird-target and the other end provided with a longitudinal slot 33, and slidably secured by means of a cross pin 34, passing through said slot 33, and carried in a swivel 35, carried beneath the housing 29. When the bird-target has been carried to one of the carrier wheels or traps 23, the suspended bird-target may be twisted about on the swivel 30, and thus be reversed and attached to the traveling carrier in its horizontal or flying position and be again despatched.

The latch engaging and actuating mechanism for engaging and carrying the bird-target in its flying position, comprises a pair of oppositely-disposed latching bolts or plates 36, adapted to be longitudinally expanded and contracted by means of eccentrically-mounted spring-resisted laterally extensible actuating bolts, each of said actuating bolts comprising a main body portion 37, a laterally extending arm portion 38, and a friction contact portion 39. One end of each of the main body portions 37, is pivotally secured to one of the latching bolts or plates 36, by means of a pivot screw 40, and the other end is pivotally secured to an actuating head 41, of an actuating expanding bolt for setting the parts in their latched engagement with the bird-target in its flying position as well as disposing the friction contact portions 39, in engagement with the adjacent sides of the upper free edges of the parts 1, forming the body of the bird-target whereby the latching bolts 36, will be withdrawn from latching engagement with the bird-target when the latter is struck by a missile shot, as hereinafter described.

The latching bolt or plates 36, together with the pivotally attached laterally extensible actuating bolts are held in their contracted or retracted position as indicated in Fig. 5, of the drawings by means of a depending longitudinally-extending spring 42, suspended beneath and connected to the latching bolts or plates 36, by means of depending supporting arms 43. The spring 42, tends to draw the latching bolts 36, toward each other when expanded as shown most clearly in Fig. 6, of the drawings, and the sensitiveness of the friction contact portions 39, of the laterally extensible actuating bolts to the impact caused by the missile shot may be regulated by regulating the distance to which the actuating bolts are moved to or past the "dead center" of the actuating head 41. In the present instance, this regulation is brought about by means of an adjusting screw 44, secured to a depending supporting stud or post 45, of one of the latching bolts or plates 36, the inner end of said adjusting

screw being adapted to abut against the main body portion 37, of one of the actuating bolts when expanded thus acting as a stop in limiting the expanding movement of 5 the same.

When it is desired to secure the bird-target to the traveling carrier in its flying position the housing portion of the traveling carrier is placed within the rectangular opening at the top of the bird-target, the upturned ends 19^a, of the carrier plate resting upon the reinforcing strips 9, above the shoulder portions 4, at the front and upon the shoulder portions of the tail stems 11, 10 above the rear shoulder portions 5, and when in this position, the latching bolts together with the laterally extensible actuating-bolts are moved to their expanded or projected position by turning the winged nut 46, of 15 the hand operated actuating or expanding bolt whereby the actuating head 41, beneath will expand the parts as shown most clearly in Fig. 6, of the drawings, and the outer ends of the latching bolts 36, will take 20 under the marginal edges of the front and rear shoulders 4, and 5, respectively. While the bird is being carried through the air in its flying position by the action of the moving carrier-wire or cable attached to the 25 traveling-carrier of the bird-target, it is obvious that should a missile shot strike any portion of the pivotally connected parts 1, of the bird-target the force or impact of the missile shot will cause the adjacent friction 30 contact portion 39, of the actuating bolt to throw the parts past "dead center" and they will be immediately contracted or retracted to the position shown most clearly in Fig. 5, of the drawings, whereby the bird-target 35 will fall and assume its substantially vertical or "dead position" as shown most clearly in 40 Fig. 3, of the drawings.

As a means for providing for what may be termed a "rear kill" the arrangement and 45 disposition of the tail 15, relative to the tail stems 11, and the oval shaped portions 1^a, is such that should a missile shot come in contact with the depending portion 15^a, it will be driven forwardly and the coaction of 50 the guide-pins 16, in the guide slots 17 together with the coaction of the contact strip 18, with the oval shaped portions 1^a, will cause the parts to be moved toward each other and thus detach the bird from its flying 55 position as above referred to.

From the foregoing description, taken in connection with the accompanying drawings, the operation and advantages of my invention will be readily understood.

Having thus described my invention without having attempted to set forth all the forms in which it may be made, or all the modes of its use, I declare that what I claim and desire to secure by Letters Patent is,—

1. An artificial bird-target, comprising a traveling trolley carrier, an artificial laterally-expansile bird-target body normally carried in a flying position, and means for disengaging and changing the position of 70 said bird-target from a flying to a "dead position" when said target body is contracted by the impact of a missile-shot.

2. An artificial bird-target, comprising a traveling carrier, an artificial laterally extensible bird-target normally carried thereby in a flying position, means for detaching said bird-target from its flying position when struck by a missile-shot and independent suspending means for causing said bird-target to assume a "dead position" when detached from its flying position. 75 80

3. In an artificial bird-target, a target-body comprising expansile parts connected to each other and conforming in their outline and contour to the outline and contour of the bird represented, and a traveling carrier for supporting said target body in a flying position when the parts are expanded, and a movable tail member in coöperative 90 relation thereto. 85

4. In an artificial bird-target, a traveling carrier comprising a trolley-wheel and housing and a carrier plate, laterally-extensible actuating bolts carried thereby, expansile 95 latching-bolts connected to said actuating-bolts, and an operating-bolt for manually extending said actuating-bolts.

5. In an artificial bird-target, the combination with a target-body comprising two 100 laterally expansile parts pivotally connected at their lower edges and provided with carrier provided with latching mechanism and laterally-extensible actuating-bolts interposed between said laterally-expansile 105 parts and independent connecting means for suspending said target-body in a "dead position" when detached from said latching mechanism.

6. In an artificial bird-target, a pair of 110 carrier-wheels, a carrier wire mounted thereon, a traveling-carrier provided with a trolley-wheel mounted on the upper member of said carrier-wire and a carrier-plate secured to the adjacent ends of the lower member of said carrier-wire, and a laterally expansile target-body normally carried by said traveling-carrier in a flying position and adapted to be contracted and detached from said carrier-plate when struck by a missile shot. 115 120

7. In an artificial bird-target, the combination with a laterally-expansile target-body composed of two parts pivotally connected at their lower portions and provided at their rear with tail stems and oval-shaped rear portions; of a tail member slidably connected to said tail-stems and provided with a depending portion adapted to coöperate with said oval-shaped rear portions whereby said target-body is contracted when said tail 125 130

member is driven forwardly by the impact of a missile-shot.

8. An artificial bird-target, comprising a traveling carrier, an artificial laterally expandible bird-target carried thereby in a flying position, means for detaching said bird-target from said position when contracted by the impact of a missile-shot, and a link-bar connecting said bird-target with said carrier whereby said target is caused to assume and is suspended in a "dead position" when detached from its flying position.

9. An artificial bird-target, comprising a main body portion made up of two metallic parts pivotally connected at their lower edges and provided at their upper portions with front and rear shoulder portions and an intermediate carrier-receiving-opening, a traveling carrier mounted in said opening and provided with latching plates taking under said shoulder portions and laterally extensible actuating bolts in expanded engagement with the upper portions of said metallic parts, and a link connected to said carrier and main body portion for suspending the latter when detached from said latching plates.

10. An artificial bird-target, comprising a target-body made up of two parts pivotally connected at their lower edges and having laterally expandible upper portions, a

traveling carrier provided with laterally extensible actuating-bolts interposed between said upper portions and latching mechanism in latching engagement with said target-body when said actuating bolts are expanded, means for manually extending said actuating-bolts, and means for suspending said target-body in a "dead position" when released from said latching mechanism.

11. An artificial bird-target, comprising a carrier, means for supporting and moving said carrier, an expandible bird-target body, means for expanding and connecting said target body in a flying position on said carrier, and independent means for suspending said target body in a dead position when disconnected from said expanding and connecting means.

12. An artificial bird-target, comprising a traveling carrier, an expandible bird-target body normally carried in a flying position, and independent means on said carrier for dropping and supporting said bird-target body in a "dead position" when the latter is contracted by the impact of a missile shot.

In testimony whereof I have affixed my signature, in presence of two witnesses.

EDWARD E. THRESHER
